UNITED STATES PATENT OFFICE.

MELVIN P. ALLEN, OF OTTAWA, KANSAS.

DESIGN FOR A HAT-BAND PROTECTOR.

SPECIFICATION forming part of Design No. 31,844, dated November 14, 1899.

Application filed October 18, 1899. Serial No. 734,021. Term of patent 14 years.

To all whom it may concern:

Be it known that I, MELVIN P. ALLEN, a citizen of the United States, residing at Ottawa, in the county of Franklin and State of Kansas, have invented and produced a certain new and original Design for Hat-Band Protectors; and I do declare the following to be a full, clear, and exact description of the invention, such as will enable others skilled in the art to which it appertains to make and use the same.

The invention relates to a new and original design for hat-band protectors; and it consists of a design of the configuration shown in the accompanying drawings, in which—

Figure 1 is a perspective view of the design, and Fig. 2 is a side elevation.

The leading feature of the design comprises the two vertical parallel side pieces 1, the lower ends of which are bent laterally, as shown at 2, thence back upon themselves, as shown at 3, thence upwardly, as shown at

4, parallel with the side pieces 1, and thence downwardly, as shown at 5, and pointed. The upper ends of the side pieces are connected by an inverted-arch piece 6. In use the arched piece 6 is inserted between the crown of the hat and its band with the laterally-bent portions 2 3 projecting outward from the hat, so that when the hats are packed in nested order the hat-bands will not be damaged by crowding one hat too far into the other.

What I claim is—

The new and original design for a hat-band protector, as herein shown and described.

In testimony whereof I have hereunto set my hand in presence of two subscribing witnesses.

MELVIN P. ALLEN.
